UNITED STATES PATENT OFFICE.

ALFRED G. VALE, OF NEW YORK, N. Y., ASSIGNOR TO THE AMERICAN TOBACCO COMPANY, OF NEW YORK, N. Y., A CORPORATION OF NEW JERSEY.

TOBACCO-PACKAGE.

1,251,598.

Specification of Letters Patent.

Patented Jan. 1, 1918.

Application filed June 19, 1917. Serial No. 175,609.

To all whom it may concern:

Be it known that I, ALFRED G. VALE, a citizen of the United States, residing at New York, in the county of New York and State 5 of New York, have invented new and useful Improvements in Tobacco-Packages, of which the following is a specification.

This invention relates to the packaging of merchandise and has particular application 10 to the wrapping or enveloping of manufactured products, such as cigars or cigarettes which are liable to be injuriously affected in constant handling or by atmospheric changes or conditions.

15 In the present instance, by way of illustration, I have shown and described my invention as employed in connection with the packaging of cigarettes, but I wish it to be understood that it is not limited in its use- 20 ful application to this particular purpose, as it is available for the packaging of other articles and products.

Cigarettes are packaged for sale in the open market in various ways, such as in slide 25 boxes, hinged card-board boxes and pouch-like envelopes or wrappers. Under some conditions the last named manner of packaging the cigarettes is preferable, as for instance, where a relatively large number of 30 cigarettes, for example twenty, constitute a pack, because under such circumstances the employment of a relatively large, stiff, cumbersome and expensive box is avoided, and at the same time, the pouch-like package, 35 owing to its flexibility, may be conveniently and comfortably carried about in the pocket. In addition, it also possesses certain advantages from the standpoint of cheapness of cost in production.

40 The usual form of pouch package embraces a composite sheet of tinfoil and paper which is completely folded or wrapped about the cigarettes, foil-sheet outward, and the cigarettes so wrapped are then inserted

45 in a small paper pouch or cup having a permanently open mouth, which leaves one end of the composite wrapper sheet exposed. The revenue stamp is then employed to seal the mouth of the package, one end portion of

50 the stamp being attached to the paper pouch while the opposite end is folded over and pasted to the adjacent portions of the composite wrapper sheet which overlie the top ends of the cigarettes.

There are certain disadvantages incident 55 to the usual form of pouch-package, among which might be mentioned the liability of the pouch to crush or collapse under rough handling or undue pressure, thus causing the breaking or destruction of the cigarettes, 60 and also the difficulty of keeping the cigarettes packed in orderly array after the mouth of the package has once been opened. This last disadvantage is due to the fact that when the revenue stamp is once broken and 65 the folds or tucked-in portions of the wrapper sheet at the mouth of the package opened outward to remove a cigarette, these folds cannot be readily restored to or maintained in their original position, for even if they 70 be carefully pressed back to overlie the ends of the cigarettes they will have a tendency to fly open again, thus exposing the cigarettes, and in many instances, permitting the latter to escape from the pouch. In fact, under 75 some conditions of handling and subjection to pressure, the ordinary cigarette pouch when once opened loses all semblance to a pouch-like container and will break down to such an extent as to no longer adequately 80 hold and protect the cigarettes.

These disadvantages of the ordinary cigarette pouch now in use are entirely obviated by my invention, for I propose to package 85 the cigarettes in such a manner and to provide such a pouch-like package that the cigarettes will not only be properly confined in orderly array within the package until the last one is withdrawn therefrom, but they will also be protected and preserved from 90 breakage due to the crushing or collapsing of the pouch.

Another purpose of my invention is to provide a pouch wherein the article, such as cigarettes, may be removed singly through a 95 relatively small opening made in the package by rupturing, tearing or ripping a small section of the wrapper sheet, the major portion of the package being maintained complete and in closed condition so that in addition to avoiding the disarrangement and accidental escape of the cigarettes, the latter will also be protected from being affected by atmospheric conditions and changes.

Furthermore, in the use of my improved 100 pouch, the liability of the fingers contacting with or striking cigarettes, other than the one which it is desired to remove is obviated,

and thus another factor to which the breakage of cigarettes in a pack is commonly due is eliminated.

I also propose to provide a cigarette package of this type which will embrace the desired features of simplicity and efficiency, coupled with economy of cost in production.

With the above recited objects and others of a similar nature in view, my invention 10 consists in the construction, combination and arrangement of parts set forth in and falling within the scope of the appended claims.

In the accompanying drawings—

15 Figure 1 is a perspective view showing the initial step in the packaging of cigarettes, and illustrating the use of a card-board shell to confine the cigarettes.

Fig. 2 is a plan view of the wrapper sheet 20 adapted to envelop the partially formed package shown in Fig. 1.

Fig. 3 is a perspective view illustrating the package after the application and folding of the wrapper sheet of Fig. 2.

25 Fig. 4 is a perspective view showing the complete package with the stamp acting as a seal for the mouth thereof.

Fig. 5 is a perspective view of the package after it has been ruptured or torn to permit 30 the removal of the cigarettes.

Fig. 6 is a view of mouth end of a modified form of package showing the tearing section of the wrapper left free to form a grasping tab.

35 Referring now to the accompanying drawings in detail, particularly to Fig. 1, the letter C indicates a plurality of cigarettes which are bunched or stacked as usual, and in the practice of my invention are first in-
40 cased by a shell 1. This shell 1 may be made from any suitable material, such as tough, durable paper, thin cardboard or the like, and in width is preferably less than the length of the cigarettes so that when the
45 blank is wrapped about the latter as shown in Fig. 1, said cigarettes will project beyond one end of the shell formed by the blank. There are a number of advantages obtainable through the use of this shell. For in-
50 stance, in addition to confining the cigarettes in orderly packed relation, it prevents the crushing or collapsing of the complete package under pressure or constant handling, and thereby obviates the liability of break-
55 ing or otherwise injuring the cigarettes. Furthermore, it assists in maintaining the neat block-like contour of the package even when most of the cigarettes in the pack have been removed.

60 The partially formed pack shown in Fig. 1 is placed upon a wrapper, such as shown at B in Fig. 2. As is usual in pouch packages of this class, this wrapper of Fig. 2 is in the nature of a rectangular, composite sheet 55 composed of a thin layer of tinfoil lined with

and united to a thin sheet of paper. This wrapper sheet B adjacent at one longitudinal edge, or that edge of the sheet which is to be folded to close the mouth of the package is scored, perforated or otherwise marked as at 2, to weaken the wrapper at this point so that the section of the wrapper bounded or inclosed by the marked lines may be grasped and readily torn or separated to form an opening in the top of the package through which the cigarettes may be removed. Such an opening is indicated by the numeral 3 in Fig. 5. In the present instance this detachable or tearable section of the blank, which is shown at 4, in Fig. 2, is in the nature of a small polygonal section, one edge or side of which is formed by the edge of the sheet itself. While the configuration of the scoring of the wrapper sheet may be such as to produce an opening of any desired shape or form, I prefer to have the score lines form a polygonal tearing section, as shown in Fig. 2, because when the wrapper sheet is completely folded about the package, as shown in Fig. 3, or Fig. 6, the perforated lines 2 of this sheet will follow the converging edges of the inter-folded portions and be so positioned as to mark out a tearing section which when removed, as shown in Fig. 5, will leave a triangular opening with the apex near the center of the top of the package. Thus the cigarettes may be easily removed through the wide base portion of the triangular opening, guided by the adjacent end wall of the package, while at the same time no great amount of material is removed from the package top, so that the opening will not be of undue size. In the folding of the wrapper to close the mouth of the package, I first tuck in the end section 7 and then fold over the marginal portions of the meeting sections of the wrapper to form the side flap or fold 8, and then fold over the opposite portion of the wrapper to form the other side fold 9. The remaining end fold of the wrapper, indicated at 10, may now be folded inward over the side fold 9, as shown in Fig. 3, and fastened in place by the usual revenue stamp shown at S in Fig. 4, or, if desired, this end fold 10 may be left free and bent downward against the adjacent end wall of the package, as shown at 10^a in Fig. 6. If the end fold 10 is sealed by the revenue stamp, in opening the package, the thumb may be inserted beneath one of the sides of the fold, as will be understood by reference to Fig. 4, and the weakened section of the wrapper torn away to present the triangular opening, as indicated in Fig. 5. If, however, this end fold 10 is left free as shown in Fig. 6, as is preferable in many instances, such end fold will constitute a tab, the purpose of which will be easily understood by the purchaser, and which tab may be readily

grasped between the thumb and one finger and torn away to form the opening.

After the wrapper has been completely folded about the cigarettes, as shown in Fig. 3, it may be inserted in the usual paper cup or pouch P, as illustrated in Figs. 4, 5 and 6, and when the revenue stamp has been applied to seal the mouth of the package, the latter will be completed and ready for the market. Of course in rupturing the wrapper sheet to form the opening for the removal of the cigarettes, the revenue stamp will also be torn or destroyed. It will be noted also that the opening will be formed in the top of the package adjacent one of the end walls of the latter and that the base line of the opening will be co-extensive with the top edge of this end wall, so that the end wall will not only form a guide for the removal of the cigarettes, but the top edge of the end wall even when the opening has been formed, will lie in substantially the same plane with the other top marginal edges of the package, thus insuring that the neat appearance and contour of the package will be retained while preserving its side wall intact.

It will further be understood that when the package has been wrapped as herein described, it will present a neat, block-like appearance with a readily discernible tearing section which may be quickly removed to permit the withdrawal of the cigarettes, while the package or container itself is at all times maintained practically intact except for this opening. The result will be that the cigarettes will also be held in proper stacked or packed alignment, and when it is desired to remove a cigarette, after the first one has been taken out, it is only necessary to tilt the package with the opening downward so as to shake or remove a cigarette through the opening, while the remaining portion of the top of the wrapper, being left in its original folded condition, will form a wall to prevent the accidental escape of the cigarettes, and this wall, bracing the entire package, will prevent the collapsing or falling apart of the wrapper.

While I have herein shown and described one particular embodiment of my invention, I wish it to be understood that I do not limit myself to all the precise details herein set forth by way of illustration, as modification and variation may be made without departing from the spirit of the invention or exceeding the scope of the appended claims.

What I claim is:

1. A wrapped package including a rectangular wrapper sheet of flexible pliable material having a continuous marginal edge provided with a plurality of interfolded portions normally closing an end of the

package, and a seal overlying such closed end and maintaining certain of the interfolded portions intact, but leaving one of such interfolded portions free to provide a grasping and tearing tab located at an end 70 edge of the package.

2. A wrapped package including a rectangular wrapper sheet of flexible pliable material having a continuous marginal edge provided with a plurality of interfolded 75 portions normally closing an end of the package, and a seal overlying such closed end and maintaining certain of the interfolded portions intact, but leaving one of such interfolded portions free to provide a 80 grasping and tearing tab located at an end edge of the package, the material of the wrapper sheet having weakened lines extending inwardly over a portion of the top of the package from points at opposite sides 85 of the tab, whereby said tab together with adjacent interfolded portions of the wrapper sheet lying within the confines of the weakened lines may be readily torn away to provide an opening at the end of the 90 package of less dimensions than the area of the closed end.

3. A wrapped package including an inclosing wrapper of flexible, pliable material provided with two pairs of oppositely arranged interfolded portions normally closing one end of the package, one pair of such interfolded portions being arranged at right angles to the other pair, one of the portions of one pair underlying the two adjacent 100 portions of the other pair and the other portion which is companion to or paired with the underlying portion, being free and constituting a means for tearing away an underlying part of the wrapper to provide an 105 opening therein of less dimensions than the area of the closed end for withdrawal of the contents thereof.

4. A package of merchandise having an inclosing wrapper sheet of flexible, pliable 110 material, one end of which is provided with three superposed infolded portions completely closing an end of the package, two of said portions each having a converging edge adjacent one side wall of the package 115 and the material of the wrapper at the wall opposite said side wall being folded to provide a substantially triangular grasping portion to permit rupture of the wrapper along lines to provide an opening therein of less 120 dimensions than the area of the closed end and through which the contents of the package may be withdrawn without unfolding the folded portions.

5. A package of merchandise having an 125 inclosing wrapper sheet of flexible, pliable material, one end of which is provided with three superposed infolded portions completely closing an end of the package, two of said portions each having a converging 130

- edge adjacent one side wall of the package and the material of the wrapper at the wall opposite said side wall being folded to provide a substantially triangular grasping portion to permit rupture of the wrapper along lines to provide an opening therein of less dimensions than the area of the closed end and through which the contents of the package may be withdrawn without unfolding the folded portions, and a seal overlying such end of the package and maintaining the major portion of such end in closed relation after the opening has been formed.
6. A cigarette package including a shell of relatively stiff material embracing the cigarettes of the package, said shell being of less depth than the length of the cigarettes whereby the latter will project beyond one end of the shell, a flexible pliable blank wrapped about the shell and cigarettes to inclose the same, said blank being interfolded at one edge portion to constitute a closed end for the package, a portion of said closed end being adapted to be torn away to form an opening of less dimensions than the area of such closed end, to permit the grasping of the ends of the cigarettes projecting beyond the shell and allow such cigarettes to be withdrawn from the package.
- 5 10 15 20 25
- In testimony whereof I have hereunto set my hand.
- ALFRED G. VALE.
